ATTORNEY

UNITED STATES PATENT OFFICE.

ROBERT SORGAN, OF NEW YORK, N. Y.

CAP OR COVER FOR JARS, BOTTLES, GLASSES, OR THE LIKE.

1,229,341.

Specification of Letters Patent. Patented June 12, 1917.

Application filed March 11, 1916. Serial No. 83,447.

To all whom it may concern:

Be it known that I, ROBERT SORGAN, a citizen of the United States, resident of New York city, county and State of New York, have invented certain new and useful Improvements in Caps or Covers for Jars, Bottles, Glasses, or the like, of which the following is a specification.

The present invention relates to improvements in caps or covers for jars, bottles, glasses or the like. With the type of caps heretofore in use, a special form of upper edge was required on the receptacle to cooperate with the cap in holding the same thereon, and special apparatus was required for binding the cap on the receptacle, or else the cap was pressed on the plain upper edge of a receptacle, and would depend upon wax or other such preparation for maintaining the same closed, and great difficulty was experienced in removing the same. Also widely different changes in temperature would tend to cause these caps to become unduly loose or tight, thereby endangering the preservation of the contents in one case, and making the cap difficult of removal in the other. It is an object of the present invention therefore to provide an improved cap which will have an elastically expansible rim portion which may be placed upon the plain edge of the glass, merely by downward pressure thereon, and will form a very tight and secure closure which will in no way be affected by weather conditions, because of the property of the rim to expand and contract slightly. A further object is to provide means whereby the cap may be readily removed when desired without danger of breaking the receptacle, and without requiring a great amount of physical exertion.

With these and other objects in view my invention is shown in the accompanying drawings, and will be hereinafter more fully described with reference thereto and finally pointed out in the claims.

In the accompanying drawings:

Figure 1 is a perspective view of my improved cap.

Figs. 2 and 3 are enlarged fragmentary views of the exterior and interior respectively of the rim portions thereof.

Fig. 4 is a top view of the cap.

Fig. 5 is a bottom view.

Fig. 6 shows the same in position on a glass.

Fig. 7 is a similar view with parts broken away showing the cap ready for removal.

Figs. 8, 9 and 10 are enlarged detail sectional views showing the cap before placing on glass, after placing thereon, and ready for removal and

Fig. 10^a is a diagrammatic view showing the action which takes place when the cap is placed on the receptacle.

Similar reference characters indicate corresponding parts throughout the several figures of the drawings.

Referring to the accompanying drawings, and more particularly to Figs. 1 to 3 thereof, my improved cap comprises an upper or body portion 10 having an annular depending rim portion 11, the top being slightly wider than the rim as at 10^a. An annular groove or recessed portion 12 is provided in the upper portion 10 annularly spaced from the rim 11 the material being stamped or forced downwardly from the said upper portion to conform substantially to the upper edge of the receptacle to be capped, and forming on the under side of the cap an annular ridge which forces the rubber ring 13 into conformity with the upper edge of the receptacle, as hereinafter more fully pointed out.

The rim 11 of the cap is provided intermediate the upper portion 10 of the cap and the lower edge with a plurality of indentations 14, slightly spaced apart, and extending inwardly from the outer surface, thereby forming a plurality of projections 15 spaced on the interior of the rim. The contour of the indentation 14 is tapering outwardly and downwardly toward the lower edge. The contacting surface of the projections 15 is slightly within the outer surface of the receptacle to be capped, and the lower edge of the rim is slightly without the said outer surface of the receptacle, so that the same may be readily set thereon without pressure. The rim is rendered slightly elastic by the indentations therein. The lower edge of the rim is formed with a curled bead 17 which forms a strengthening or stiffening portion to the rim. At one point in the rim there is provided a cutout portion 18 preferably triangular in shape, the horizontal portion thereof being adjacent the stiffening edge 17, which is of sufficient strength to hold the rim in its proper shape.

In Figs. 8, 9 and 10 I have shown in detail the manner in which the cap is applied to the receptacle, and in Fig. 10^a I have shown diagrammatically the action which takes place.

Referring to these figures, the cap is first loosely placed upon the glass, so that the projections 15 rest on the upper edge of the same. These projections it will be clearly seen extend slightly within the outer surface of the receptacle. Downward pressure is then applied to the cap preferably by a machine for this purpose and by reason of the elasticity of the indented portion of the rim the projections are forced over the top of the receptacle and form a tight surface contact therewith. It is preferable that the capping machine be such that it will extract air from the receptacle during the capping operation. By means of the gradual forcing out of the rim, as shown clearly in Fig. 10^a, the resiliency of the cap is maintained. During this forcing out of the rim, the top of the cap is forced inwardly, this action reducing the vacuum space within the receptacle and also aiding in the locking of the cap on the receptacle. By reason of the spaces between the projections there is no air compression within the receptacle until the rubber ring comes into contact with the rim of the receptacle, and at this point practically all of the air is exhausted. At the same time the rubber ring 13 will be made to conform to any slight irregularities in the upper edge thereof, such as may be caused by chipping or in the manufacture by reason of the pressure exerted by the annular recessed portion 12, and the secure manner in which the cap is held to the receptacle, so that an absolutely air tight closure is made. When it is desired to remove the cap, the portion of the stiffening edge 17 at the triangular cut out portions 18 is snapped or broken by any suitable instrument, and the rim by means of its elasticity, and the stiffness of the edge 17, is sprung outwardly as clearly shown in Figs. 7 and 10, and the cap may be readily lifted from the receptacle.

I have illustrated preferred and satisfactory forms of my invention, but it is obvious that changes may be made therein within the spirit and scope thereof, as defined in the appended claims.

I claim:

1. The combination with a receptacle of a closure therefor, comprising a top, a downwardly depending unbroken rim portion, having a plurality of inwardly extending closely adjacent projections, having a slight elasticity, the annular inner pre-attachment diameter of which is less than the outer diameter of the rim of the receptacle, and the interior contacting surface of the rim

adapted to be slightly expanded over the receptacle, the inner diameter of said projections in said extended position being substantially equal to the outer diameter of the rim of said receptacle, said closure being retained thereon in said expanded and tensioned position by frictionally binding contact with said rim of the receptacle.

2. The combination with a receptacle of a closure therefor, comprising a top, a downwardly depending unbroken rim portion, having a plurality of inwardly extending closely adjacent projections, having a slight elasticity, the annular inner pre-attachment diameter of which is less than the outer diameter of the rim of the receptacle, and the lower edge of said rim portion being turned upon itself to form a strengthening and stiffening portion, the interior contacting surface of the rim adapted to be slightly expanded over the receptacle and be retained thereon in said expanded position by frictional contact with said rim of the receptacle.

3. The combination with a receptacle of a closure therefor, comprising a top, a downwardly depending unbroken rim portion provided with a plurality of indentations, slightly spaced apart forming projections on the interior of the said rim, the inner pre-attachment diameter of which is less than the outer diameter of the rim of the receptacle, the said plurality of projections rendering the rim slightly elastic, the interior contacting surface of the rim adapted to be slightly expanded over the receptacle, the inner diameter of said projections in said extended position being substantially equal to the outer diameter of the rim of said receptacle, said closure being retained thereon in said expanded and tensioned position by frictionally binding contact with said rim of the receptacle.

4. An improved receptacle closure, comprising a top, a downwardly depending unbroken rim portion, having a slight elasticity, the lower edge of the said rim portion being turned upon itself to form a strengthening and stiffening portion, the said rim being provided at one part with a cut out portion disposed adjacent the said strengthening rim portion, the interior contacting surface of the rim adapted to be slightly expanded over the receptacle to be capped, the closure adapted to be removed from the receptacle by breaking of the said strengthening portion of the rim at the said cutout portion thereof.

5. The combination with a receptacle having a plain substantially cylindrical rim portion, of a closure therefor, comprising a top, a downwardly depending rim portion having a plurality of inwardly extending closely adjacent projections having a slight elasticity, the annular inner surfaces of said

projections being inclined inwardly and upwardly, and being of a pre-attachment diameter less than the outer diameter of the rim of the receptacle, the interior contacting surface of the rim adapted to be slightly expanded over the receptacle, said projections adapted to assume an uninclined contacting position with respect to said rim of said receptacle to be retained thereon in said 10 expanded position by frictional contact with said rim of the receptacle.

6. The combination with a receptacle of a closure member, comprising a top having an annular recess therein, slightly within 15 the inner diameter of the rim of said receptacle, a downwardly depending rim portion having a plurality of inwardly extending closely adjacent projections, having a slight elasticity, the annular inner pre-attachment 20 diameter of which is less than the outer diameter of the rim of the receptacle, a

yielding closure ring disposed between the upper edge of said receptacle and said closure, and extending beneath said recessed portion of the top of said closure, the interior contacting surface of the rim of said closure adapted to be slightly expanded over the receptacle, and to be retained thereon in said expanded position by frictional contact with said rim of the receptacle, said yielding closure ring adapted to be slightly forced within said receptacle by said recessed portion on the top of said closure to form an air tight closure therewith.

In testimony that I claim the foregoing 35 as my invention, I have signed my name in presence of two subscribing witnesses.

ROBERT SORGAN.
